UNITED STATES PATENT OFFICE.

FREDERICK H. N. GERWIG, OF BRADDOCK, PENNSYLVANIA.

METHOD OF IGNITING BLAST FURNACES.

Application filed April 12, 1923. Serial No. 631,550.

To all whom it may concern:

Be it known that I, FREDERICK H. N. GERWIG, a citizen of the United States, and resident of Braddock, in the county of Allegheny and State of Pennsylvania, have invented certain new and useful Improvements in Methods of Igniting Blast Furnaces, of which the following is a specification.

10 This invention relates to methods of lighting and blowing in blast furnaces, and has for one of its principal objects the provision of a method of this class that is far superior to the methods heretofore practiced in that it requires less labor and less material, is quicker, cheaper, and provides for a more perfect ignition and even combustion of the charge.

Heretofore, it has been the practice to either build a platform in the furnace hearth at approximately the level of the cinder notch, or to fill the hearth with coke up to about this level, and then to fill the remainder of the hearth and major portion 25 of the bosh with cord wood, which wood must be loaded into the furnace by manual labor, and then to fill coke and limestone on top of this wood until the major portion of the shaft is filled and then to add 30 several rounds of burden, and to finally light the wood by thrusting heated iron bars or the like through the tuyère openings.

Various slight modifications of the above 35 method have been practiced but in each instance the core of cord wood has been used, and all of the known prior methods of lighting and blowing in blast furnaces have been more costly and slower than the 40 method of this invention.

When using the cord wood core the gases formed by the combustion of the wood invariably permeated through the bosh and found their way into the cast house and surrounding structures, in some cases causing the gassing of the workmen and always materially handicapping the workmen operating the furnaces.

Another disadvantage of the prior methods was that sparks from the burning wood would be carried up through the furnace and ignite the gas at the top of the furnace, thus often causing considerable damage to the furnace top.

55 In the present method no wooden core is employed and, therefore, the disadvantages

and objections thereto are entirely overcome.

Broadly, the present method consists in filling the furnace with a solid body of coke 60 from the bottom of the hearth up to approximately the top of the bosh with the exception of a relatively small quantity of readily combustible material adjacent each tuyère, then filling the shaft of the furnace 65 with a combination of coke and limestone for a considerable height, then adding a plurality of rounds of burden and finally igniting said readily combustible material.

In the drawings, Figure 1 is a diagrammatic sectional elevation through a furnace loaded in accordance with my improved method and ready for lighting.

Figure 2 is an enlarged sectional elevation of the lower part of a furnace loaded in accordance with my invention.

Figure 3 is a transverse section on the line III—III of Figure 2.

Figures 4 and 5 are side elevations taken at right angles to each other, and Figure 6 80 is a top plan of one of the flue-like members adapted to contain the readily combustible material.

Figure 7 is a side elevation and Figure 8 is an end elevation of one of the burner 85 frames adapted to be mounted in the tuyère openings.

Figure 9 is a side elevation of one of the electric igniters used to ignite the readily combustible material.

Referring more particularly to the drawings, the furnace illustrated is of the usual construction and consists of a well or hearth 2, bosh 3, mantle support 4 and shaft 5.

The hearth is provided with the usual tuyères 6, cinder notch 7 and iron notch 8. The tuyères 6 are provided with the usual blow pipes 9 connected by the penstock pipes 10 with the bustle pipe 11 to supply a blast of air to the furnace.

In carrying out my invention approximately 25 skips of coke are filled into the furnace hearth 2 and leveled to approximately the contour of the dotted line A—A of Figures 1 and 2. That is, this bed of coke is leveled up over the hearth slightly below the tuyères 6, with the exception of the point adjacent the cinder notch 7, where it is tapered slightly to permit the entrance of workmen and material through the notch 110 for carrying on the next operation.

After the first bed of coke has been lev-

eled up in the hearth a plurality of wooden flue-like boxes 12 are passed through the cinder notch 7 and manually placed in position in front of each tuyere. The boxes 12 are secured together by wooden strips 14 or other tying means.

The boxes 12 have a closed bottom 15 and may be made in two sections, as clearly shown in Figure 5 and secured together by strips 16. This will facilitate their passage through the cinder notch. Each of the boxes 12 is provided adjacent its lower end with an opening 17 adapted to be placed opposite the tuyere mouth.

After the boxes 12 are secured in position the penstock cap 18 is removed and a wooden burner frame 19 is passed through each blow pipe and tuyere and entered into the opening 17 of the boxes.

The boxes 12 are then filled with readily combustible material 20, such as kindling wood and coal, and form what may be termed individual furnaces.

After the boxes 12 are all filled with readily combustible material the workmen leave the furnace through the cinder notch and an additional charge of coke approximating 35 skips is filled into the furnace, which will fill the furnace to approximately the top of the bosh with a solid core of coke, with the exception of the boxes 12 and their readily combustible material 20.

After this additional charge of coke, alternate layers of limestone and coke are filled into the furnace until the shaft is approximately two-thirds filled. The quantity of limestone used is very small compared with the quantity of coke, only sufficient limestone being used to flux the ash of the coke.

After the furnace shaft is thus partially filled with the combined limestone and coke charge approximately 20 rounds of burden are charged to complete the filling of the furnace. Each round of burden generally consists of 1 skip of ore, 1 skip of combined ore and limestone, 2 skips of coke, 1 skip of ore, 1 skip of combined limestone and ore and 2 skips of coke, charged in the order set forth.

It will be understood that quantities given in this specification are only approximate and may be varied according to the requirements of any given furnace.

After the furnace is filled as above described it is ready for lighting. The lighting is done by the electric lighters 24 which are inserted through the peep holes in the penstock caps 18 and are supported on the wooden burner frames 19. A small quantity of excelsior waste 25 or the like is placed in the penstock pipes 10 adjacent the rear end of each burner frame, so that a flame may be readily formed by the lighters.

The lighters 24 are composed of a length

of metallic conduit 26 having a resistance coil 27 on its forward end having conductors 28 and 29 leading therefrom through the conduit 26 to a switch 30 on the rear end, which controls the circuit to the coil 27. The switch 30 has lead wires 31 leading therefrom to a suitable plug 32 adapted to be attached to a suitable service receptacle 33 in the electric supply line 34, which is controlled by a main switch 35.

After all the lighters are positioned, care is taken to see that all the switches 30 are closed and everything is in readiness for the actual lighting of the furnace. The main switch 35 is then closed and the circuit is completed simultaneously through all the lighters 24, causing them to glow and thereby igniting the material 25 causing a burst of flame, which is carried through the blow pipes 9 into the boxes 12. The burner frames 19 serve as additional fuel and aid in igniting the material in the boxes 12. If desired, when the current is turned through the lighters 24 a slight blast may be turned into the furnace. However, this is not always necessary, since the natural draft of the furnace is sufficient to cause combustion.

By igniting all the boxes 12 simultaneously a uniformly lighted furnace results which is a very desirable feature, since it will cause a uniform descent of the stock.

The small amount of readily combustible material used is quickly consumed and is only sufficient to properly ignite the coke, and this method differentiates from all prior methods by its lack of the wood core heretofore used.

While I have described and illustrated the preferred embodiment of my invention it will be understood that various modifications may be practiced without departing from the scope of my invention as defined in the appended claims.

I claim:

1. The method of lighting and blowing in a blast furnace, which consists in filling the furnace with coke to a point slightly below the tuyeres, then providing a quantity of more readily combustible material accessible from each of the tuyeres of the furnace, then continuing the filling of the furnace with a solid body of coke to approximately the top of the bosh, then filling the shaft of the furnace for a considerable height with alternate layers of limestone and coke, the coke predominating materially over the limestone in quantity, and finally adding a plurality of rounds of burden and then igniting said readily combustible material.

2. The method of lighting and blowing in a blast furnace, which consists in filling the furnace with coke to a point slightly below the tuyeres, then providing a quantity of more readily combustible material adjacent each of the tuyeres of the furnace, then con-

- tinuing the filling of the furnace with a solid body of coke to approximately the top of the bosh, then filling the shaft of the furnace for a considerable height with alternate 5 layers of limestone and coke, the coke predominating materially over the limestone in quantity, then adding a plurality of rounds of burden, and then igniting said readily combustible material.
- 10 3. The method of lighting and blowing in a blast furnace, which consists in filling the furnace with coke to a point slightly below the tuyères, securing a combustible hollow flue-like member in front of each tuyère, 15 filling each of said flue-like members with readily combustible material, continuing the filling of the furnace with a solid body of coke to approximately the top of the bosh, then filling the shaft of the furnace for a 20 considerable height with alternate layers of limestone and coke, the coke predominating materially over the limestone in quantity, then adding a plurality of rounds of burden and then igniting said readily combustible 25 material.
4. The method of lighting and blowing in a blast furnace, which consists in filling the furnace with coke to a point slightly below the tuyères, securing a combustible hollow 30 flue-like member in front of each tuyère, said flue-like members being provided with openings accessible from the outside of the furnace through said tuyères, filling each of 35 said flue-like members with readily combustible material, continuing the filling of the
- furnace with a solid body of coke to approximately the top of the bosh, then filling the shaft of the furnace for a considerable height with alternate layers of limestone and coke, then adding a quantity of burden on 40 top of the coke, inserting lighters through each of the tuyères and simultaneously lighting the material in each of said flue members.
5. The improvement in methods of lighting and blowing in blast furnaces, which consists in filling the furnace with a solid body of coke from its base up to approximately the top of the bosh with the exception of a relatively small quantity of readily 45 combustible material adjacent each tuyère, then filling the shaft of the furnace with a combination of coke and limestone for a considerable height, then adding burden and then igniting said readily combustible material.
6. The improvement in methods of lighting and blowing in blast furnaces which consists in providing a flue-like member filled with readily combustible material in front of each tuyère, then filling said furnace from the hearth to a point adjacent the top of the shaft with material, none of which is more readily combustible than coke and igniting 50 the readily combustible material to cause 55 the ignition of the remainder of the charge.

In testimony whereof, I have hereunto set my hand.

FREDERICK H. N. GERWIG.
